United States Patent Office

Des. 215,910
Patented Nov. 4, 1969

215,910

TEXTILE FABRIC

Donald Scaglione, New York, N.Y., assignor to Dayco Corporation, Dayton, Ohio, a corporation of Delaware

Filed Oct. 1, 1968, Ser. No. 13,806

Term of patent 14 years

Int. Cl. D5—02

U.S. Cl. D92—1

The figure is a plan view of a textile fabric showing my new design, the design unit contained in the inner dot-dash lines being repeated in regular succession as indicated by the extensions beyond the unit boundaries.

I claim:

The ornamental design for a textile fabric, as shown and described.
